DOOR STOP

Edward B. Holt, Rockford, Ill., assignor to Amerock Corporation, Rockford, Ill., a corporation of Illinois

Filed Nov. 2, 1961, Ser. No. 67,366

Term of patent 14 years

(Cl. D10—7)

FIG. 2 is a side elevational view taken from the right of FIG. 1.

FIG. 3 is a side elevational view taken from bottom of FIG. 1.

FIG. 4 is an enlarged sectional view taken along the line 4—4 in FIG. 2.

I claim:
The ornamental design for a door stop, substantially as shown.
